DESIGN FOR A DISPLAY RACK

Ferdinand Kramer, Port Chester, N. Y.

Application March 6, 1946, Serial No. 127,165

Term of patent 3½ years

(Cl. D80—9)

To all whom it may concern:

Be it known that I, Ferdinand Kramer, a citizen of the United States, and a resident of Port Chester, county of Westchester, and State of New York, have invented a new, original, and ornamental Design for a Display Rack, of which the following is a specification, reference being had to the accompanying drawing, forming part thereof.

Figure 1 is a perspective view of a display rack showing my new design;

Figure 2 is a top view; and

Figure 3 is a side elevational view.

I claim:

The ornamental design for a display rack, substantially as shown.

FERDINAND KRAMER.
